[57] CLAIM

The ornamental design for a combined bottle and cap for hair tonic, as shown and described.

DESCRIPTION

FIG. 1 is a top plan view of a combined bottle and cap for hair tonic showing my new design;

FIG. 2 is a bottom plan view thereof;

FIG. 3 is a front view thereof, the rear view being identical to the front view;

FIG. 4 is a right side view thereof, the left side view being identical to the right side view;

FIG. 5 is an exploded front elevation of the combined bottle and cap for hair tonic, the rear elevation is a mirror image thereto; and,

FIG. 6 is a perspective view of the combined bottle and cap for hair tonic.
